UNITED STATES PATENT OFFICE.

GEORGE BOXLEY, OF TROY, NEW YORK.

GARMENT.

SPECIFICATION forming part of Letters Patent No. 727,070, dated May 5, 1903.

Application filed March 17, 1902. Serial No. 98,513. (No model.)

To all whom it may concern:

Be it known that I, GEORGE BOXLEY, a citizen of the United States, residing at Troy, county of Rensselaer, and State of New York, have invented certain new and useful Improvements in Garments, of which the following is a specification.

The invention relates to such improvements; and it consists of the novel construction and combination of parts hereinafter described and subsequently claimed.

Reference may be had to the accompanying drawings, and the reference characters marked thereon, which form a part of this specification.

Similar characters refer to similar parts in the several figures.

Figure 1 is a view showing my improved garment construction in use upon a person, the fly member of the waistband being unfastened, with one end thereof in an upright position and the other end folded down, exposing to view the lower edge of the shirt-waist and connecting mechanism. Fig. 2 is a similar view before the shirt-waist is applied, showing the suspender connections in position. Fig. 3 is a vertical cross-section taken on the broken line 3-3 in Fig. 1. Fig. 4 is a similar view partly in perspective, the waist and suspenders being omitted. Fig. 5 is a view in perspective of the waistband portion of the nether garment having the attaching member of the waistband in the form of tabs. Figs. 6, 7, and 8 are perspective views partly in section, illustrating modified forms of my invention. Fig. 9 is a sectional view similar to Fig. 3, further illustrating the modification shown in Fig. 8.

The object of my invention is to facilitate the manipulation of the mechanism for connecting a shirt-waist with a nether garment and to cover and conceal from view the lower edge of the waist and such connecting mechanism.

In providing for the use of shirt-waists, for men more particularly, various means have been employed for adapting the shirt-waist to connect with ordinary trousers.

In carrying out my invention it is my object to adapt the trousers or other nether garment to connect with an ordinary shirt-waist and with ordinary suspenders, if de-

sired, and to conceal from view such connections in use.

In its preferred form my invention comprises a nether garment provided with a duplex waistband open along its upper edge to receive the lower edge of a waist, said band comprising an outer fly member foldable outwardly and downwardly and an inner connecting member extending above the fold-line of the fly member and provided with means for connecting with the nether garment the lower edge of the waist, adapted to be covered and concealed by the fly member of the band.

Referring to the drawings, 1 represents a nether garment, as a man's trousers or a woman's skirt, provided at its upper end with a waistband (shown in Figs. 1, 2, 3, 4, and 8 in duplex form) comprising the outer fly member 2 and the inner attaching member 3. The band thus formed is open along its top, the outer fly member being adapted to be folded outwardly and downwardly upon the body of the garment along the line of junction of the band member therewith. When the fly member is so folded, the inner attaching member of the band is exposed to view, with its connecting mechanism, comprising buttons 4, adapted to enter buttonholes 5 in the lower edge of the waist 6, whereby said waist and nether garment may be connected together as easily as a waist could be attached to the buttons on the outside of ordinary trousers. After the waist has been thus connected with the nether garment the fly member of the waistband is restored to its normal upright position, thereby inclosing the lower edge of the waist between the band members and covering and concealing from view the lower edge of the waist and the connecting-buttons.

If suspenders are worn, the ends thereof may be connected at front and back with the buttons 4 before the waist is donned by the wearer.

I have shown in Fig. 2 suspenders 16 passing over the shoulders of the wearer and adapted to be inclosed within the waist in use.

The fly member of the band is preferably provided with means for connecting together its ends, such as the hook 7 and eye 8, the connection thereby accomplished serving to

retain the fly member in an upright position in use.

In Fig. 5 I have shown portions of the attaching member of the waistband omitted, 5 the attaching mechanism being supported by the remaining portions thereof in the form of the tabs 9.

When desired, the attaching-band member may be the ordinary waistband of the trousers, as shown at 10 in Figs. 6 and 7, provided with the usual suspender-buttons 11 on the outside thereof, in which case the fly member 12 is in the form of a separate belt connected with and supported by the trousers by means of a buttonholed band or tabs 13, adapted to connect with the trousers-buttons.

The attaching-band member may, if desired, be provided with two sets of connections adapted to engage separately with the waist and suspenders, as shown in Figs. 8 and 9, the button 14 being adapted to connect with the waist and a separate button 15, just above and in line with the button 14, 25 being adapted to connect with the suspender-end.

The connection between the attaching member of the waistband and the waist and suspenders may be accomplished in any known 30 manner by means of buttons and buttonholes or other connecting mechanism.

I am aware that fly-bands have been used upon garments and make no claim, broadly, to the same.

It is characteristic of my invention that the outer band member is connected with the inner attaching member only by a hinge connection wholly below the attaching mechanism, whereby the outer band member can be folded back throughout its length upon the body of the nether garment independently of the inner attaching member, said outer band member being provided with fastening mechanism for connecting together its ends also independently of the inner attaching member. The suspenders being connected to the inner attaching member serve to support the same in position both to facilitate the connection therewith of the waist and the folding and replacing of the outer band member.

What I claim as new, and desire to secure by Letters Patent, is—

A nether garment provided with a duplex waistband, the outer member thereof being foldable throughout its length outwardly and downwardly and connected with the inner member only by a hinge connection along its lower edge; means for fastening together the ends of the outer member independently of the inner member; and means for detachably securing between the band members the lower edge of a waist, substantially as described.

In testimony whereof I have hereunto set my hand this 13th day of March, 1902.

GEORGE BOXLEY.
